SUPPORT AND CONNECTION FOR STEAM TURBINE AND CONDENSER INSTALLATIONS

Charles D. Wilson, West Allis, Wis., assignor to Allis-Chalmers Manufacturing Company, Milwaukee, Wis., a corporation of Delaware

Application February 2, 1949, Serial No. 74,108

11 Claims. (Cl. 60—95)

This invention relates to steam or other elastic fluid turbines and more particularly to elastic fluid turbine and condenser installations, and the principal object of the invention is to provide new and improved elastic fluid turbine constructions and new and improved turbine and condenser or the like installations.

The exhaust from an elastic fluid turbine is usually received by a condenser or other heat exchanger. One of the objects of the invention is to provide a construction wherein the basement depth, or the amount the installation extends below the floor level, is reduced; that is, in particular, the lowest point of the condenser, for example, is much higher than is the case with prior installations.

In known types of installation difficulty is experienced by reason of the unequal expansion of the turbine and the condenser, so that the condenser must be supported from below by springs. Furthermore, if the condenser contains a large amount of water, the weight of this water puts an added stress on the turbine by reason of the fact that the condenser is hung from the turbine. Accordingly, another object of the invention is the provision of a construction which avoids these difficulties.

Other objects will appear hereinafter as the description of the invention proceeds.

The novel features of the invention and how the objects are attained will appear more fully from this specification and the accompanying drawing showing one embodiment of the invention and forming a part of this application, and all these novel features are intended to be pointed out in the claims.

In the drawing:

Fig. 1 is a plan view of a steam turbine and condenser installation embodying the invention, some parts being broken away for the sake of clearness;

Fig. 2 is a side elevation of the installation shown in Fig. 1;

Fig. 3 is a section taken along the line III—III of Fig. 1, looking in the direction of the arrows; and

Fig. 4 is a fragmentary section taken along the line IV—IV of Fig. 1, looking in the direction of the arrows.

In the illustrated embodiment a steam turbine 10 comprises a usual cylinder or casing 11 within which a spindle 12 is operatively disposed, the inside of the cylinder and the outer periphery of the spindle being provided with the usual co-

operating blading as will be understood by those skilled in the art.

After the steam has passed through the blading (from right to left, as viewed in Fig. 1), it enters 5 an exhaust casing portion which is here shown as comprising two portions 13, 14, extending laterally in opposite directions from the longitudinal center line of the turbine. The exhaust casing portions 13, 14 comprise a cover portion 15 which is here shown as integral with the upper half of the cylinder 11, the cylinder being divided along a horizontal plane which includes the longitudinal center line of the turbine. This horizontal plane, seen from the side of the installation, as in Fig. 2, is defined by a line 16; and seen in the section in Fig. 3, is defined by a line 10 also designated 16.

The exhaust casing portions 13, 14 further 15 comprise lateral extensions 17, 18 which are here shown as integral with the lower half of the cylinder 11. The lateral extensions 17, 18 do not extend as far laterally as the cover portion 15 and terminate in generally U-shaped upwardly open flanges 25, 26, respectively, the outer surfaces of the flanges defining vertical planes 27, 28 (see particularly Fig. 3). At their upper sides 20 the exhaust portions 17, 18 have longitudinally spaced flanges 35 and 36a, 36b, the surfaces of which are in the horizontal plane 16. The flanges 36a, 36b merge with the horizontal flanges 25 on the lower half of the turbine cylinder 11. The cover portion 15 has a flange 33 which is complementary to the flange 35 and bolted or otherwise suitably fastened thereto. The flange 33 merges with U-shaped end portions 33a and 33b which in turn merge with portions complementary to the flange portions 36a, 36b.

Disposed alongside of the exhaust casing portions 17, 18 are condensers 30, 31. These condensers may be of any suitable internal construction (not shown) whereby the steam is caused to come into heat exchanging relation with and condensed by relatively cool circulating water.

45 Referring specifically to the condenser 30, this has at its upper end a generally U-shaped inwardly open flange 32a which is complementary to and cooperates with the generally U-shaped flange portions 33a of the cover 15. The flanges 32a and 33a may be bolted together or fastened together in any other suitable way. It will be 50 evident that exhaust steam from the upper half of the turbine can enter the condenser through the opening provided within the horizontal joint between the flanges 32a, 33a.

The condenser 30 further has a generally U-shaped upwardly open flange 34a complementary to the flange 35 on the exhaust casing portion 17. The flanges 34a and 25 may be bolted together or fastened together in any other suitable way, and it will be obvious that exhaust steam from the lower half of the turbine can enter the condenser through the opening provided within the vertical joint between flanges 34a, 25.

It should not be understood, however, that there is any distinct division between exhaust steam coming from the upper and lower halves of the turbine, as it will be evident that the condenser 30 is connected to the exhaust casing portion 13 by a joint in a horizontal plane 16, and a joint in a vertical plane 27, these joints mutually communicating with each other.

The condenser 30 is supported by support means disposed on opposite sides thereof this means being here shown as comprising at one side a steel standard 40a engaged at its top by brackets or feet 41a desirably integral with the condenser shell, and at the other side by a concrete structure 42a engaged at its top by brackets or feet 43a desirably integral with the condenser shell. The support means just described serves to take the weight of the condenser so that the weight of the condenser does not come on the flanges 32a and 25.

The condenser 31 is connected to the exhaust casing portion 14, and is supported similarly to the condenser 30 as hereinbefore described, the parts being given the same reference numerals but with the suffix b.

The exhaust end of the turbine 10 is supported by means here shown as comprising a concrete structure 50 which extends transversely of the longitudinal axis of the turbine 10 below a bearing support 51. The bearing support 51 is integral with the lower half 17, 18 of the exhaust casing. The foot of the bearing support 51 engages the upper surface of the support means 50 directly or a metallic pad (not shown) may be interposed as will be understood by those skilled in the art. The plane of engagement of the bearing support 51 with its support means 50 is the same as the plane of engagement of the feet 41a, 43a, 41b, 43b with their support means.

The right hand end of the turbine 10 may be supported in a conventional or any suitable manner as will be understood by those skilled in the art.

The bearing support 51 contains a bearing for a shaft 55 driven by the spindle 12, and as here shown the shaft is adapted to drive an electric generator 56 which may be supported by the support means 42a, 42b.

The upper surface of the support means for the turbine and condensers as hereinbefore described may be taken as the floor line for the installation, this being indicated by the line 60 (Fig. 2).

It will be evident that the invention materially reduces the necessary basement depth, and that the hereinbefore mentioned difficulties are obviated. It is to be noted in particular that the condensers are not hung from the turbine casing but are separately supported, and, more particularly, are supported at the same level as is the turbine casing. The condensers are hung free of the basement floor, and no supporting springs are required.

From the foregoing it will be apparent to those skilled in the art that the illustrated embodiment of the invention provides new and improved

turbine and condenser installations and accordingly accomplishes the objects of the invention. On the other hand, it will also be obvious to those skilled in the art that the illustrated embodiment of the invention may be variously changed and modified, or features thereof, singly or collectively, embodied in other combinations than those illustrated, without departing from the spirit of the invention, or sacrificing all of the advantages thereof, and that accordingly the disclosure herein is illustrative only, and the invention is not limited thereto.

It is claimed and desired to secure by Letters Patent:

1. An elastic fluid turbine and condenser installation, comprising: an elastic fluid turbine having an exhaust casing portion; a condenser; means for connecting said exhaust portion to said condenser, said connecting means comprising a joint in a horizontal plane and a joint in a vertical plane; first means engaging and supporting said exhaust portion and second means engaging and supporting said condenser, said condenser being engaged by said second supporting means at the same level as said exhaust portion is engaged by said first supporting means.

2. An elastic fluid turbine and condenser installation, comprising: an elastic fluid turbine having an exhaust casing portion including portions extending laterally in opposite generally horizontal directions from the longitudinal center line of said turbine; separate condensers connected to said laterally extending exhaust portions; first supporting means disposed between said condensers for engaging and supporting said exhaust portion and second supporting means having a portion disposed between said condensers for engaging and supporting said condensers, said condensers being engaged by said second supporting means at the same level as said exhaust portion is engaged by said first supporting means.

3. An elastic fluid turbine and condenser installation, comprising: an elastic fluid turbine having an exhaust casing portion including portions extending laterally in opposite generally horizontal directions from the longitudinal center line of said turbine; separate condensers disposed adjacent the outlets of the respective laterally extending exhaust portions; and means for connecting each of said condensers to its respective exhaust portion, each connecting means comprising a joint in a horizontal plane and a joint in a vertical plane.

4. An elastic fluid turbine and condenser installation, comprising: an elastic fluid turbine having an exhaust casing portion; a condenser; means for connecting said exhaust portion to said condenser; said connecting means comprising cooperating horizontal flange means on said exhaust portion and on said condenser, and cooperating vertical flange means on said exhaust portion and on said condenser; first means engaging and supporting said exhaust portion and second means supporting and engaging said condenser, said condenser being engaged by said second supporting means at the same level as said exhaust portion is engaged by said first supporting means.

5. An elastic fluid turbine and condenser installation, comprising: an elastic fluid turbine having an exhaust casing portion including portions extending laterally in opposite generally horizontal directions from the longitudinal center line of said turbine; and separate condensers

connected to said laterally extending exhaust portions; and means for connecting said condensers to said laterally extending exhaust portions comprising cooperating horizontal flange means on said laterally extending exhaust portions and said condensers, and cooperating vertical flange means on said laterally extending exhaust portions and said condensers.

6. An elastic fluid turbine and condenser installation, comprising: an elastic fluid turbine having an exhaust casing portion including portions extending laterally in opposite generally horizontal directions from the longitudinal center line of said turbine; separate condensers connected to said laterally extending exhaust portions; means for connecting said condensers to said laterally extending exhaust portions comprising cooperating horizontal flange means on said laterally extending exhaust portions and said condensers, and cooperating vertical flange means on said laterally extending exhaust portions and said condensers; supporting means having a portion disposed between said condensers engaging and supporting said exhaust portion and said condensers respectively.

7. An elastic fluid turbine and condenser installation, comprising: an elastic fluid turbine having an exhaust casing portion including portions extending laterally in opposite generally horizontal directions from the longitudinal center line of said turbine; separate condensers connected to said laterally extending exhaust portions; means for connecting said condensers to said laterally extending exhaust portions comprising cooperating horizontal flange means on said laterally extending exhaust portions and said condensers, and cooperating vertical flange means on said laterally extending exhaust portions and said condensers; first supporting means disposed between said condensers for engaging and supporting said exhaust portion and second supporting means having a portion disposed between said condensers for engaging and supporting said condensers, said condensers being engaged by said second supporting means at the same level as said exhaust portion is engaged by said first supporting means.

8. An elastic fluid turbine and condenser installation, comprising: an elastic fluid turbine having an exhaust casing portion including portions extending laterally in opposite generally horizontal directions from the longitudinal center line of said turbine; separate condensers disposed adjacent the outlets of the respective laterally extending exhaust portions; and means for connecting each of said condensers to its respective exhaust portion, each connecting means comprising cooperating horizontal flange means on each of said laterally extending exhaust portions and each of said condensers respectively, and cooperating vertical flange means on each of said laterally extending exhaust portions and each of said condensers respectively.

9. An elastic fluid turbine and condenser installation, comprising: an elastic fluid turbine having an exhaust casing portion including portions extending laterally in opposite generally

horizontal directions from the longitudinal center line of said turbine; separate condensers disposed adjacent the outlets of the respective laterally extending exhaust portions; and means for connecting each of said condensers to its respective exhaust portion, each connecting means comprising a joint in a horizontal plane and a joint in a vertical plane, the location of said horizontal joint being at upper portion of respective condenser.

10. An elastic fluid turbine and condenser installation, comprising: an elastic fluid turbine including an exhaust portion divided along a horizontal plane which includes the longitudinal center line of said turbine, said exhaust portion comprising a lower portion beneath said horizontal plane laterally terminated by a vertical joint surface which defines an outwardly directed opening on each side of said center line, and a cover portion above said horizontal plane having a horizontal joint surface in said plane on each side of said center line which defines downwardly directed openings laterally beyond and adjacent respectively to said vertical joint surfaces; and a condenser disposed on each side of said exhaust portion each having joint surfaces complementary to corresponding joints on said exhaust portions.

11. An elastic fluid turbine and condenser installation, comprising: an elastic fluid turbine having a cylinder including an exhaust portion divided along a horizontal plane; said exhaust portion comprising a lower portion beneath said horizontal plane laterally terminated by a vertical joint surface which defines an outwardly directed opening on each side of the center line of said turbine, and a cover portion above said horizontal plane having a horizontal joint surface in said plane on each side of said center line which defines downwardly directed openings laterally beyond and adjacent respectively to said vertical joint surfaces; and a condenser disposed on each side of said exhaust portion each having joint surfaces complementary to corresponding joints on said exhaust portions.
